To all whom it may concern:

Be it known that I, Emil M. Bonyhady, have invented a new, original, and ornamental Design for a Slipper, of which the following is a specification, reference being had to the accompanying drawing, forming a part hereof.

The dominant feature of the design resides in the specific configuration of the strap elements, which elements are substantially twice as wide through the center as at each end resulting in oppositely projecting jogs near the ends, in association with the trimming extending from the inside of the strap across the back portion thereof and ending at the rearwardly projecting jog.

I claim:

The ornamental design for a slipper, as shown and described.
